UNITED STATES PATENT OFFICE

146,241

DESIGN FOR A SERVICE CARRIAGE

Joseph A. Wiser, Manhattan Beach, Calif.

Application February 23, 1946, Serial No. 126,863

Term of patent 7 years

(Cl. D14—3)

To all whom it may concern:

Be it known that I, Joseph A. Wiser, a citizen of the United States and a resident of Manhattan Beach, in the county of Los Angeles, State of California, have invented a new, original, and ornamental Design for Service Carriage, of which the following is a specification, reference being had to the accompanying drawing, forming part thereof.

of a service carriage showing my new design, and

Figure 2 is a side and front end perspective view taken when looking at the opposite side from that shown in Figure 1.

I claim:

The ornamental design for a service carriage, as shown.

JOSEPH A. WISER.
